UNITED STATES PATENT OFFICE.

HERBERT G. BEEDE, OF PAWTUCKET, RHODE ISLAND.

THREAD-GUIDE SUPPORT.

1,064,279.

Specification of Letters Patent. Patented June 10, 1913.

Application filed May 19, 1910. Serial No. 562,168.

To all whom it may concern:

Be it known that I, HERBERT G. BEEDE, a citizen of the United States, residing at Pawtucket, in the county of Providence and 5 State of Rhode Island, have invented certain new and useful Improvements in Thread-Guide Supports, of which the following is a specification.

My invention relates to thread guide supports for spinning and twisting machines, and the object of my invention is to improve upon the construction of a thread guide support as now ordinarily made, and to provide a strong and durable thread guide support, 15 of simple and inexpensive construction.

My invention consists in certain novel features of construction of my improvements as will be hereinafter fully described.

In my improvements in thread guide support, I preferably make the support of cast metal, and in three parts, one of said parts is the stationary part, detachably secured to the thread board or bar by screws, and has two open side bosses thereon, to loosely receive cylindrical projections on one of the other parts, to form a hinge connection between the two parts. The second part, which is hinged to the first mentioned part, is the movable part. Combined with the 25 movable part is a third part, which is adjustably attached to the movable part, and acts to secure to said movable part the thread guide. The thread guide is preferably made of wire and has an open end eye 30 on its outer end, and a closed eye on its inner end. The thread guide is adjustable out and in, and also in the direction of the length of the thread guide support, and is held in its adjusted position by said third 35 part, which is secured to the other movable part by two screws.

In connection with my improved thread guide support I may use a separate plate or block on the front edge of the thread board, which forms a stop for the movable part of the thread guide support when it is moved into its raised position; said stop or block fits into a groove or recess in the front edge of the thread board, and is held 45 therein by the screws which attach the stationary part of the thread guide support to the thread board, all as will be hereinafter 50 fully described.

Referring to the drawing:—Figure 1 is a 55 plan view of a detached section of a thread board or bar, and a thread guide support,

embodying my improvements attached thereto. Fig. 2 is a section, on line 2, 2, Fig. 1, looking in the direction of arrow *a*, same figure; the broken lines show the 60 raised position of the movable part. Fig. 3 is a front edge view of the parts shown in Fig. 1, looking in the direction of arrow *b*, same figure, with the thread guide removed. Fig. 4 is a bottom or underside view of the 65 movable part of the thread guide support, detached. Fig. 5 is an edge view of the stationary part of the thread guide support, and the movable part, detached from the thread board, and showing the position of 70 the movable part relatively to the stationary part, when it is desired to disconnect said parts.

In the accompanying drawing, 1 is a detached section of a thread board or bar, 2 is 75 the stationary part of the thread guide support, which is shown attached to the front edge of the thread board or bar 1. The stationary part 2 is preferably made of cast metal, with two openings therethrough to 80 receive the attaching screws 3, and two bosses 2' on its upper edge, one at each end. The bosses 2' are open on their inner side at 2'', as shown in Fig. 5. Extending out from the front side of the stationary part 85 2, at each end thereof, and in alinement with and directly in front of the bosses 2' are projections 2''', see Fig. 3.

Combined with the stationary part 2 is the 90 movable part of the thread guide support, which is preferably made of cast metal, and consists of the part 4, of rounded shape on its rear edge, and provided with two cylindrical projections 4', see Fig. 4, which are adapted to loosely extend into the two bosses 95 2' on the stationary part 2. The rounded rear edge portion of the part 4 is connected with the body of said part by a reduced portion or web 4^b which is of a thickness somewhat less than the width of the openings at 100 2'' at the inner sides of the bosses 2', for a reason which will hereinafter appear. The movable part 4 has preferably upon its underside a longitudinal groove or recess 4'', see Fig. 2, and two elongated openings 4''' 105 therethrough, each to receive a screw 5, which extends loosely through an opening in the third part 6, forming the cap or holding piece for the thread guide wire 7. The screws 5 enter threaded holes in the nuts 8, 110 which extend within the recess 4'' in the part 4, and are thus prevented from turn-

ing, see Fig. 2. The part 6, forming the attaching cap for the guide wire 7, is recessed upon its underside, as shown by broken lines at 6', Fig. 1, to loosely receive 5 the eye 7' on the inner end of the thread guide wire 7, and allow said wire to be moved in and out, and held in its adjusted position by tightening the screws 5. The thread guide wire 7, and also the cap or 10 holding piece 6, may be adjusted in the direction of the length of the thread guide support, by moving the screws 5 in the elongated holes 4''' in the part 4. The part 4 has in this instance projections 4^a on its 15 lower side, see Fig. 2, which rests on the projections 2''' on the stationary part 2, to hold the thread guide support in a horizontal plane.

In connection with the thread guide support above described, I may use a separate plate or block 9, which extends in a groove or recess in the front edge of the thread board or bar 1, and has a lip or extension 9' on its upper end which extends upon the 20 upper edge of the thread board or bar 1, see Fig. 2, and a projection or extension 9'' on its opposite side, at its lower edge, which extends in a recess in the lower edge of the stationary part 2 of the thread guide support, see Fig. 3. The plate or block 9 is held in the recess in the thread board or bar 25 by the stationary part 2, which is secured to said board or bar by the screws 3, as above described. When the movable part 30 of the thread guide support is raised, as shown by broken lines in Fig. 2, the reduced portion thereof, on its inner side, will rest on the upper edge of the plate or block 9, which acts to form a stop, and hold the 35 movable part of the thread guide support in its raised position as shown in Fig. 2.

From the foregoing it will be understood that my improved thread guide support, aside from the plate or block 9 and the attaching 45 screws and nuts, consists of only three simple parts which may be of cast or drop-forged metal, if desired, so as to require little or no finishing, or which may be of sheet metal pressed into shape. 50 In attaching the movable part 4 to the stationary part 2, in assembling the parts, the part 4 is caused to assume the position shown in Fig. 5 so as to bring the reduced part or web 4^b into longitudinal register 55 with the openings 2'' between the ends of the bosses 2' and the body of the part 2, and then by sliding the part 4 endwise relative to the part 2 the openings back of the cylindrical projection 4' may be brought into 60 register with the bosses 2', when the part 4 is turned over forward, on the hinge afforded by the engaged cylindrical parts 4' and bosses 2', to the position shown in Figs. 1 and 2, to bring the parts into working position. 65 When it is desired to detach the part

4 from the part 2 (the latter being dismounted from the thread board or bar 1) the said part 2 is turned over backward to the position shown in Fig. 5 and then by an endwise sliding movement, the said parts 70 may be detached from each other, the web 4^b sliding freely through one or the other of the openings 2'' between the bosses 2' and the body of the part 2.

It will also be observed that the construction herein shown and described provides means whereby the thread guide 7 may be adjusted either in or out or sidewise, when the screws 5 are loosened. The rectangular recess, shown in dotted lines in Fig. 1, 80 loosely receiving the eye 7' at the inner end of the thread guide, permits of the in and out adjustment, while the longitudinal adjustment of the plate 6, by virtue of the slots 4''' in the plate 4, permits a lateral 85 or sidewise adjustment of the thread-guide, as hereinbefore stated.

The nuts 8 on the screws 5 are prevented from turning with said screws, when the latter are tightened or loosened, by reason 90 of the engagement of the said nuts with the side walls of the recess 4'' in which said nuts are received.

It will be understood that the details of construction of my improvements may be 95 varied if desired.

Having thus described my invention, what I claim as new and desire to secure by Letters Patent is:—

1. A thread guide support, for spinning 100 and twisting machines, consisting of a stationary metal part adapted to be secured to the thread board or bar and having open bosses at its ends, a second or movable metal part having a rounded rear edge portion 105 with cylindrical ends separated by openings from the body of said part, said rounded rear edge portion being connected with the body of the said movable part by a reduced portion or web of a thickness which is less than the width of the openings between said 110 bosses and the body of said stationary part, and means for attaching a thread guide to said movable part, said means comprising a clamping plate or block and attaching 115 screws, and the said movable part having slots through which said screws may pass, to afford a sidewise or lateral adjustment of the thread guide.

2. A thread guide support, for spinning 120 and twisting machines comprising a pivoted part, as 4, having a longitudinal recess, as 4'', on its under side, and slots, as 4''', and a clamping plate attached to said pivoted part by screws passing through said slots 125 and provided with nuts fitting in said recess.

3. A thread guide support, for spinning 130 and twisting machines, comprising a pivoted part, as 4, having a longitudinal recess, as 4'', on its under side, and slots, as 4''', 135

and a clamping plate attached to said pivoted part by screws passing through said slots and provided with nuts fitting in said recess, said clamping plate having a recess 5 on its under side to loosely receive an eye on the thread-guide to permit an in and out adjustment of the said thread guide, and said slots permitting lateral adjustment of said clamping plate, carrying the said thread 10 guide with it.

4. A thread guide support, for spinning and twisting machines, consisting of three main parts, to wit, a metal part adapted to be screwed to the thread board or bar, and 15 having open bosses at its ends, a second or movable metal part having a rounded rear edge portion with cylindrical ends separated by openings from the body of said movable part, said rounded rear edge portion being 20 connected with the body of said movable part by a web or portion of a thickness less than the width of the openings between the said bosses and the body of the said first-named part, and a third part or clamping 25 plate, combined with a thread guide, and

means for adjustably securing said third part or clamping plate to said second or movable part, said third part or clamping plate having a recess on its under side to permit an in and out adjustment of the 30 thread guide, combined with a block or plate on the thread board or bar to engage said movable plate and hold it in raised position.

5. A thread guide support, for spinning or twisting machines, consisting of a stationary 35 part to be attached to the thread board or bar, a movable part hinged to said stationary part, and means for attaching a thread guide to said movable part, said attaching means being constructed to permit the adjustment 40 of the thread guide, both in and out and laterally, and comprising a clamping plate having a recess on its under side and which is mounted for lateral adjustment on said movable part.
